A. J. PICHL.

CARBURETER.

APPLICATION FILED JAN. 7, 1918.

1,293,908.

Patented Feb. 11, 1919.

UNITED STATES PATENT OFFICE.

ANTHONY J. PICHL, OF ST. LOUIS, MISSOURI, ASSIGNOR TO WESTERN AUTOMOBILE COMPANY, OF ST. LOUIS, MISSOURI, A CORPORATION OF MISSOURI.

CARBURETER.

1,293,908.

Specification of Letters Patent. Patented Feb. 11, 1919.

Application filed January 7, 1918. Serial No. 210,658.

To all whom it may concern:

Be it known that I, ANTHONY J. PICHL, a citizen of the United States, residing at St. Louis, Missouri, have invented a certain 5 new and useful Improvement in Carbureters, of which the following is a full, clear, and exact description, such as will enable others skilled in the art to which it appertains to make and use the same, reference 10 being had to the accompanying drawings, forming part of this specification.

My invention relates generally to carbureters and more specifically to means capable of being easily and conveniently operated for accurately regulating and controlling the quantity or volume of liquid hydrocarbon, such as gasoline, that is drawn by suction from the spray nozzle of the carbureter, and which passes in vapor form 20 to the combustion chamber of the engine.

The principal object of my invention is to provide simple and efficient means whereby the flow of volatile fuel which forms the basis of combustion in the engine cylinder 25 may be very accurately controlled and regulated.

A further object of my invention is to provide regulating means preferably in the form of a valve which operates entirely in 30 dependent of the valve which controls the flow of air to the carbureter and also independent of the valve which controls the flow of liquid hydrocarbon from the source of supply to said carbureter.

Another object of my invention is to associate with my improved valve, suitable operating connections, the latter capable of being actuated from a point a considerable 35 distance away from the carbureter, for instance, on the steering post near the steering wheel, or from the dash of the vehicle having a carbureter equipped with my improved gasoline control valve.

With the foregoing and other objects in 40 view, my invention consists in certain novel features of construction and arrangement of parts, hereinafter more fully described and claimed, and illustrated in the accompanying drawings, in which—

Figure 1 is an elevational view of a portion of a carbureter and a portion of a motor vehicle steering post and showing my invention applied thereto.

Fig. 2 is a vertical section through the 45 lower portion of a carbureter and showing

my improved gasoline control valve associated therewith.

Fig. 3 is an elevational view of the valve detached from the carbureter.

Fig. 4 is an enlarged detail sectional view 60 of the upper end of the gasoline discharge nozzle within the carbureter and showing the valve which is associated with said nozzle in full open position.

Fig. 5 is a plan view of an operating lever 65 for my improved valve and which lever is adapted to be positioned on the steering post of a vehicle.

Fig. 6 is a sectional view of a clamp 70 which is adapted to be applied to the steering post and upon which the operating lever for the valve is mounted.

Referring by numerals to the accompanying drawings which illustrate a practical embodiment of my invention, 10 designates 75 the lower part of a carbureter of ordinary construction and operating therein is the usual float 11 which actuates a valve (not shown) and which latter controls the admission of liquid hydrocarbon or gasoline to 80 the chamber 12 within member 10.

Centrally arranged within member 10 is a member 13 provided with a nozzle chamber 14 and seated in the bottom of said member 13 and projecting upwardly into 85 said chamber 14 is a tubular nozzle 15, the upper end thereof being provided with a tapered jet or spray opening 16. Ports 17 establish communication between the lower portion of chamber 12 with the opening or 90 passageway through nozzle 15. It will be understood that the parts just described are of ordinary and well-known construction.

The valve contemplated by my invention includes a rod 18, the upper end of which 95 is tapered as designated by 19 and of such size as to fit snugly in the tapered jet or spray opening 16. This rod is arranged to slide freely through a suitable cylindrical member 20, the upper portion 21 of which is 100 externally threaded and seated in a depending portion 22 of the carbureter body 10.

Screw-seated in the lower portion of the cylindrical body 20 is a gland or packing nut 23 through which the lower portion of 105 rod 18 slides freely. Formed integral with or fixed to the lower portion of the body 20 and depending from one sidethereof is a short bracket 24, the same serving as a bearing for a short horizontally disposed shaft 25. 110

Formed on one end of this shaft is a comparatively short crank 26 and journaled therein is a laterally bent lower end 27 of rod 18.

- 5 Secured in any suitable manner to the end of shaft 25 opposite the end provided with the crank 26 is a short crank arm 28 to the lower end of which is pivotally connected one end of an operating rod 29. This rod can 10 be extended to any convenient point remote from the carbureter, but where the carbureter equipped with my improved valve is utilized in connection with the internal combustion engine of a motor vehicle, I prefer to 15 extend said rod along the steering column of the vehicle. This rod is necessarily flexible to a certain degree and where it is extended along the steering column, I prefer to inclose it in a housing, such as a small tube 30, the 20 latter being secured to the column in any suitable manner.

As a convenient means for shifting the rod 29 lengthwise to regulate the position of the valve, I prefer to connect the upper end of 25 said rod to a short operating lever such as 31, the same being pivotally connected to a bracket 32 which is located on the steering column adjacent to the wheel at the upper end thereof. If desired, a portion of this 30 bracket 32 may be corrugated or provided with notches as designated by 33 against which latter the lever 31 bears, thus providing simple means for holding said lever in its adjusted position.

35 The operation of my improved valve will be readily understood, for by proper manipulation of lever 31, the shaft 25, through the connections 29 and 28, is rocked, thereby shifting the position of crank 26 and moving 40 rod 18 lengthwise through the nozzle 15.

When the valve is closed, the tapered upper end 19 of rod 18 fits snugly in the tapered jet or spray opening 16, as shown in Fig. 2; and when the valve is in its full open 45 position, rod 18 and tapered end 19 occupies the position shown in Fig. 4.

As illustrated in Figs. 2 and 4, the normal gasoline level is in a plane slightly below the extreme upper end of nozzle 15, and when 50 rod 18 is drawn downward to partially open or unseat the valve, a proportionate amount of liquid gasoline will be drawn upwardly through the tapered opening 16 on each intake or suction stroke of the engine.

By proper manipulation of the lever 31, my improved valve can be easily and quickly

shifted to any intermediate position between full open and full closed, thereby effecting a positive and accurate regulation and control of the amount of volume of gasoline passing from the nozzle of the carbureter into the mixing and vaporizing chamber thereof, and from the latter to the cylinders of the engine, this regulation, of course, being dependent on the conditions under which the engine is operating and accomplished by the operator from his seat in the vehicle.

The particular form of device herein illustrated and described is particularly intended for use in connection with a number of carbureters now manufactured and on the market, and it can be readily applied to these carbureters without change in their structure.

It will be understood that no limitation is necessarily made to the precise structural details herein disclosed, but that changes, alterations and modifications within the scope of the claims may be resorted to when desired.

I claim:

1. The combination with a carbureter having a jet nozzle through which liquid hydrocarbon is adapted to pass, of a tubular member seated in the carbureter, a valve member mounted for reciprocating movement in said tubular member, the inner end of which valve member is adapted to close the passageway through the jet nozzle, a bell crank mounted for operation on the outer portion of said tubular member, one arm of which bell crank is connected to the reciprocating valve member, and means for actuating said bell crank.

2. The combination with a carbureter having a jet nozzle through which liquid hydrocarbon is adapted to pass, of a tubular member seated in the carbureter, a valve member mounted for reciprocating movement in said tubular member, the inner end of which valve member is adapted to close the passageway through the jet nozzle, a bell crank mounted for operation on the outer portion of said tubular member, one arm of which bell crank is connected to the reciprocating valve member; a rod connected to the other arm of the bell crank, which rod extends a substantial distance away from the carbureter and an operating lever connected to said rod.

In testimony whereof I hereunto affix my signature this 28th day of December, 1917.

ANTHONY J. PICHL.
